UNITED STATES PATENT OFFICE.

LAURENCE E. TOPHAM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

INSOLE.

1,421,619.

Specification of Letters Patent. Patented July 4, 1922.

Application filed August 14, 1918. Serial No. 249,857.

To all whom it may concern:

Be it known that I, LAURENCE E. TOPHAM, a citizen of the United States, residing at Swampscott, in the county of Essex and State of Massachusetts, have invented certain new and useful Improvements in Insoles; and I do hereby declare the following to be a full, clear, and exact description of the invention, such as will enable others skilled in the art to which it appertains to make and use the same.

This invention relates to insoles for boots and shoes and more particularly to what are known commercially as manufactured insoles. Such insoles are generally produced from two or more layers of sheet insole material and when so constructed are called laminated insoles. The improvement herein-after described is applicable especially to 20 laminated insoles.

In the manufacture of laminated insoles for welt shoes it has heretofore been customary to build a body portion of several layers of insole material, the combined thickness of which forms the feather outside the marginal sewing-rib. This feather thickness has been uniform throughout the periphery of the feather. The thickness of the upper materials, which are lasted into 30 the angle formed by the sewing-rib and feather and over the heel end of the insole, is not uniform, however, there being a considerable extra thickness at the end portions of the upper caused by the insertion at the toe of the box-toe and additional toe stiffening materials, and the insertion at the heel of the counter the forward ends of which overlap the rear ends of the sewing-rib. By reason of this the welt, when seated 40 upon the upper, the shoe being then in inverted position, rests in a higher plane relative to the base of the sewing-rib at the end portions of the insole than throughout the remainder of the shoe. Consequently considerable difficulty is experienced by the operator of the inseaming machine in sewing around the toe and adjacent the breast line. If the operator sews "high," which is a natural consequence of the raised position of the welt, a weak inseam results and consequently when the outsole is attached the latter is held above its proper plane at the toe and the correct line of the shoe is lost. If the sewing-rib is too low to per-

mit the welt to be sewed "high," the operator will tip the shoe so as to sew "full" and the long stitch thus formed through the rib or between substance will be exposed in the welt crease of the completed shoe, producing what is termed a "grinning" inseam which detracts from the appearance of the shoe.

The object of the present invention is to produce a laminated insole having a feather which is fitted so as to overcome the difficulties incident to the operation of sewing the upper materials to the insole because of the variation in the thickness of the upper materials just referred to, and which will result in superior shoe making on any type of shoe.

In accordance with this object a feature of the present invention provides that, the feather of the insole shall be so fitted that room is provided for the extra upper materials wherever they occur with the result that in welt shoes the welt lies properly against the sewing-rib and insures an inseam at a uniform height above the tread face of the insole, whereby the proper lines of the shoe are preserved. To this end it is proposed to reduce the thickness of the feather where necessary by removing a portion of one of the layers of insole material which are used to construct the laminated insole. Such a reduction in feather thickness is provided, as herein shown, about the toe, substantially from one end of the tip-line to its other end and, preferably, also at each side of the shank for a short distance forward of the breast-line. Preferably the layer which provides the sewing-rib will not be disturbed, the reduction being made in a body-layer and the width of the portion removed measured inward from the edge of the sole, will be substantially equal to the width of the feather. In a laminated insole composed of three layers the reduction will preferably be made in the central layer. Those skilled in the art will recognize that an insole having the characteristics defined will add quality, accuracy and perfection to shoemaking since its use overcomes all irregularity and lack of uniformity heretofore present in sewing the upper to the insole.

The invention comprises an insole having the novel features of construction here-

inafter described and claimed, and illustrated in the accompanying drawings showing its preferred form, in which:

Figure 1 is a plan view showing the ribbed 5 or sewing-face of a welt insole; Figs. 2 and 3 illustrate the appearance of the inseam at the toe of a shoe when using the old and the new insoles, respectively in welt work; and Fig. 4 is a fragmentary view, in perspective, showing the method of reducing 10 the feather at the toe.

The type of insole illustrated in the drawings is a laminated insole for welt shoes composed of three layers of insole material. 15 Although no specific kind of material is essential, it is preferred to use a textile fabric, such as duck, for one outside layer 5 forming the sewing-surface, said layer being provided with a marginal sewing-rib 6, 20 which may be molded therein at the desired location relative to the edge of the insole, and a feather 7. The remaining layers form the body-layers, the other outside layer 8 forming the sock-surface being preferably 25 a leather skiving equal in area to the area of the unribbed or smooth face of the layer 5. The central body-layer 9 is preferably a leather substitute, such as fiberboard, and is so fitted as to permit the operator of the 30 inseaming machine to sew the seam at a uniform height relative to the face of the insole, thus preserving the correct lines in the finished shoe, as already explained.

The fitting of the body-layer 9 consists in 35 shaping the blank to provide an area equal to the area of the unribbed face of the layer 5, or of the layer 8, except at the toe or at the heel end of the shank just forward of the breast line but preferably at both ends. 40 The purpose of this special fitting is to provide a reduction in the thickness of the feather at the portions of the insole where the overlaid upper materials are increased in thickness by reason of the addition of 45 stiffening materials such as the box toe and counter, and thus compensate or make room for the reception of such extra thickness. Accordingly a strip extending completely around the toe is removed or omitted from 50 the margin of the body layer 9, as shown best in Fig. 4, the recess 10 thus formed terminating substantially at the tip line, indicated by the shoulders 11 and 12, since the increased thickness of upper materials at 55 the toe does not extend back of this line. The feather 7 of the sewing-surface, then lies in contact with the sock-surface layer throughout the recess 10 forming a feather of but two layers about the toe whereas ad- 60 jacent portions of the feather are formed of all three layers. The advantage accruing from fitting the insole in the manner just described will be apparent to those skilled in the art from an inspection of Figs. 65 2 and 3. Fig. 2 shows an inseam sewed

"high" and the consequent distortion in the line of the welt crease due to the abrupt rise at the tip line on to the box toe where the insole feather is of uniform thickness, and Fig. 3 shows the even line of the inseam 70 obtained when the insole of the present invention is used, thus preserving the correct line of the welt crease and providing an even surface on which to lay the outsole.

The same difficulty with respect to the 75 proper lay of the inseam occurs, as already pointed out, at the heel end of the insole due to the fact that the forward ends of the counter must be lasted to the sewing-rib where said ends project forwardly beyond 80 the breast line. Accordingly marginal strips are removed or omitted from the body-layer 9 adjacent the rear ends of the sewing rib, as shown best in Fig. 1 where the sewing-surface 5 is broken away at one 85 side to show one of the recesses 13 and 14 thus formed. These marginal strips are of substantially the same width as the feather, like the strip removed from the toe and the same advantages are secured from their re- 90 moval and consequent reduction in feather thickness as are secured at the toe end of the insole. Preferably the rear ends 15 and 16 of the recesses 13 and 14 are beveled to avoid a shoulder where the counter runs 95 up on to the heel-seat which if present would interfere with a proper laying of the outsole.

It is believed unnecessary to describe the process of manufacture of the insole except 100 to say that the three layers are preferably formed separately to the desired shape, the sewing-rib 6 for a welt insole being molded in the layer 5 and the marginal strip or strips being removed or omitted from the 105 layer 9 prior to the assembly of the layers on each other. When assembled the layers are secured together, preferably by an adhesive applied at some convenient time, and, in the process of making, the insole may be 110 molded to any desired contour.

While the invention is herein disclosed for the purpose of elucidation in an insole of the kind used in the manufacture of welt shoes, it is to be understood that it is applicable to the production of manufactured insoles for shoes of other types, the true scope of the invention being found defined in the appended claims.

The nature and scope of the invention 120 having been indicated and its preferred embodiment having been specifically described, what is claimed as new, is:

1. A manufactured insole comprising a plurality of layers of insole material one of 125 which is provided with a marginal sewing-rib and forms the sewing-surface, the feather of the insole being formed of the combined thickness of all of said layers except at an end portion of the insole where that part of 130

- a layer which would lie beneath the feather portion of the sewing-surface layer is omitted.
2. A manufactured insole comprising a body-layer of insole material having a strip along its margin forward of the tip line cut away, said strip being substantially equal in width to the feather and including the edge of the body-layer, and a layer provided with a marginal sewing-rib and continuous feather forming a sewing surface, the feather at the toe of said sewing-surface layer lying within the recess formed by the cut away portion of the feather of said body-layer.
- 15 3. A manufactured insole comprising a layer provided with a marginal sewing-rib forming a sewing-surface, a sock-surface layer and a central body-layer, said body-layer being cut away at an end portion of the insole between the sewing-rib and the edge of the insole permitting the sewing layer at this point to lie in contact with the sock-surface layer.
- 25 4. A manufactured insole comprising three layers of insole material the two outside layers being equal in area to each other, and the central layer being also equal in area to the others except for a marginal strip removed from the tip portion thereof thereby forming a feather at the toe reduced in thickness relative to adjacent portions thereof.
- 35 5. A manufactured insole comprising three layers of insole material the two outside layers, one of which is provided with a marginal sewing rib, being equal in area to each other, and the central layer being also equal in area to the others except for the removal of short marginal strips extending forward of the breast-line on each side of the shank, said outside layers being secured in contact over the recesses thus produced, thereby forming a feather on each side at the heel end reduced in thickness relative to adjacent portions thereof.
- 40 45 6. A manufactured insole comprising three layers of insole material the two outside layers being equal in area to each other, and the central layer being also equal in area to the others except for marginal strips removed from the tip portion thereof and from each side of the heel portion thereof adjacent the breast line thereby forming a feather at both ends of the insole reduced in thickness relative to adjacent portions thereof.
- 50 7. A manufactured insole comprising three layers of insole material two of which are of equal area and the third of which has a marginal strip extending to the edge of the sole removed from an end portion thereof to form an edge at said end reduced in thickness relative to the thickness of adjacent portions of the edge.
- 55 8. A manufactured insole comprising a plurality of layers of insole material of which one is of less area than the remainder, said decrease in area being caused by the removal of a marginal strip extending to the edge of the sole from about the toe end of said layer to reduce the edge thickness of the insole at the toe.
- 60 70 9. A manufactured insole comprising a plurality of layers of insole material of which one is of less area than the remainder, said decrease in area being caused by the omission from said layer of a marginal strip extending to the edge of the insole to reduce the edge thickness of the insole at that point relative to the thickness of adjacent portions of the edge and to compensate for an extra thickness of upper materials at the toe.
- 65 75 80 10. A manufactured insole comprising three layers of insole material, the two outside layers, one of which is provided with a marginal sewing-rib, being equal in area to each other and the central layer being also equal in area to the others except for the omission of marginal strips, said outside layers being secured in contact in the recesses thus produced and thereby forming an edge of different thicknesses to compensate for the different thicknesses of upper materials at the corresponding portions of the shoe in which the insole is to be incorporated.

LAURENCE E. TOPHAM.
